MECHANICAL IRONING DEVICE

Edwin E. Foster, Austin, Tex., assignor to Majik-Ironers, Inc., Austin, Tex., a corporation of Texas

Application October 6, 1934, Serial No. 747,241

19 Claims. (Cl. 38—30)

The present invention relates to a mechanical ironing device and is an improvement over the ironing device in accordance with my co-pending application for Letters Patent Serial No. 683,218, filed August 1, 1933, now Patent No. 2,027,274, dated January 7, 1936.

The object of the present invention is to provide an ironing device having a mechanical arm and mounted adjacent an ironing board. The 10 mechanical arm is constructed as simply as possible with a minimum of moving parts. The iron and arm are counterbalanced and when the iron is forced onto and contacts with the ironing board, which force is very slight, the iron 15 automatically receives a force equal to that required to iron successfully so that the operator need not apply any pressure on the board. It is thus only necessary to push the iron laterally over the board, and when the weight of the operator's hand is removed from the handle of the iron, the iron is raised automatically by the arm of the iron to leave the iron suspended a few 20 inches above the board.

The advantages of a mechanical ironing device 25 according to the present invention are as follows:

It is not necessary to lift the iron at any time nor is it necessary to "ride" the iron during ironing as the mechanical arm does all the work of lifting, lowering and pressing the iron on the board. For this reason the iron itself is extremely light and in its suspended position it is easily pushed or pulled out of the way without undue manual effort. A slight push down on 30 the handle of the iron will result, when the iron touches the board, in the mechanical arm forcing the iron downwardly on the board with all the pressure necessary for perfect ironing. The cord for the electric current for heating the iron 35 enters at the end of the arm and thus the electric wires are provided in the arm to the iron so that the cord is at all times completely out of the way and well protected. The iron cannot fall off the board as it is permanently secured 40 to the mechanical arm. Also it cannot cause fires or scorching by remaining on the board when not in use as the iron is forced upwardly by the mechanical arm a slight distance the instant the hand is removed from the handle of 45 the iron. The arm of the ironing device uses no electric current as it is entirely mechanical. Finally the entire ironing device can be neatly and easily folded up and stored away as a compact and portable household appliance.

The foregoing are all advantages and objects of the present invention but others will suggest themselves when the following description is taken into consideration together with the accompanying drawings. As an example the mechanical arm is operated by a single spring which not only acts as a counterbalance for the arm and iron but also supplies the pressure necessary to force the iron on the board when the iron touches the board and continues to press the iron 10 on the board during the entire ironing procedure.

The drawings show a form of the invention in which the same reference numerals indicate corresponding or similar parts throughout the 15 several views and in which:

Fig. 1 is a front-side view of the entire mechanical ironing device,

Fig. 2 is a top view of the entire device,

Fig. 3 is an end-side view of the entire device 20 on a somewhat larger scale,

Fig. 4 is a side view of the iron and its arm together with the mechanical operator for the arm.

Fig. 5 is a top view of a portion of the arm 25 partly in section,

Fig. 6 is a longitudinal section of the iron and a portion of the arm,

Fig. 7 is a vertical sectional view of the mechanical operator and a portion of the arm, 30

Fig. 8 is a cross-sectional view of the operator taken on line 8—8 of Fig. 7,

Fig. 9 is a cross-sectional view of the operator taken on line 9—9 of Fig. 7,

Fig. 10 is a fragmentary side view of a portion 35 of the operator,

Figs. 11 to 14 are diagrammatic side views illustrating the operator in four different positions,

Fig. 15 is a cross-sectional view of the universal 40 joint in the iron, and

Fig. 16 is a top view of the iron with a number of parts removed.

The complete device as shown in Figs. 1 to 3 includes a preferably tubular frame 1 having a 45 plurality of legs 2, an ironing board 3 mounted on the frame 1, and an iron operator 4 supporting the arm 5 and the iron 6 and mounted on the frame 1. The entire machine can be folded up by unscrewing the legs 2, loosening the bolts 50 7 and by rotating the operator 4 270° clockwise (Fig. 3) around the linear pivot 8 (Figs. 3, 4 and 7) as a center so that the operator, arm and the iron will be adjacent the bottom surface 55 of the board.

Electric current is brought to the device by an electric cord 9 and a switch plug 10 to the top of the arm 5 at the junction of the arm 5 and operator 4.

5 The iron 6 is mounted on the arm 5 as shown in Figs. 4 to 6. The arm 5 is jointed so that it comprises two sections 11 and 12 movably connected together by the joint 13. A lever system passes through the arm portions 11 and 12 and 10 through the joint 13 and consists of a lever 14 pivoted at 15 in the arm 11. A lever 16 is pivoted at 17 in the arm 12 and both arms in the joint 13 are connected to each other by a pull rod 18. The other end of the lever 16 is connected to an operating rod 19 which extends from the end of the arm 5 into the operator 4.

The operator 4, Figs. 7 to 14, comprises a stationary frame member 20 rigidly secured to the frame 1 of the entire device. A movable member 21 carries the arm 5 and is mounted to move vertically by means of interconnecting links 22 connecting the members 20 and 21 in the form of a parallelogram.

As shown in Figs. 7 to 10, two links 22 are provided at the lower end of the parallelogram, Fig. 7, and one link on the upper end, Fig. 8. The lower links 22 are interconnected by means of a bar 23. The parallelogram, therefore, comprises the members 20 and 21 and the links 22.

30 A bracket 24 is secured to the member 21 by means of screw 25 and a cap screw 26. A double arm 27 is pivotally connected to the bracket at 28 and has one end of a spring 29 secured thereto by means of an adjustable link 30 mounted 35 on a pin 31. This link 30 is adjustable by means of the set screw 32. A section 33 extends across the arm 27 to which the operating rod 19 is secured. The other end of the spring 29 is connected to a pin 34 secured to a bracket 35 which 40 in turn is fastened to the upper link 22.

As clearly shown in Fig. 9 the lower links 22 are mounted on ball-bearings 36 which are maintained in place by screws 37 in shafts 38.

The operation of this parallelogram arrangement is as follows:

Referring to Figs. 11 to 14, Fig. 12 shows the vertically movable member 21 of the four bar linkage in its extreme upward position. The spring 29 has a slight tension therein but is in 50 its unstretched position. Fig. 11 shows the parts in the half-way position in which the distance between a center line of the spring 29 to the point B is less than the distance between a center line of the spring 29 to the point B in Fig. 12. In 55 other words the effective lever arm for tensioning the spring lessens as the member 21 moves downward and therefore compensates for the fact that the tension on the spring increases. In Fig. 13, the member 21 has travelled still lower so that 60 the points C and D almost coincide but the spring 29 still continues to lift upward with about the same force that it did at the beginning or middle of the stroke. At this position the iron would be adjacent to the board. Then the 65 weight of the hand of the operator upon the handle of the iron moves the arm 27 upwardly as shown in Fig. 14. In this position the spring is pulling downward. When the arm 27 is in line with the upper link 22, the spring is neither 70 pulling upwardly or downwardly. By providing the stops 39 adjustable on the member 21 the lifting force and the pressure force may be easily adjusted to any combination. Thus the throw-over of the arm 27 takes place preferably before 75 C and D attain coincidence.

The iron 6 is mounted on the section 11 of the arm 5 by means of a swivel joint arrangement as shown in Figs. 6 and 15. The section 11 terminates into a collar 39' which is surrounded by a ring 40. A second ring 41 surrounds the ring 5 40, and by means of pins 42 threaded into the rings and collar a swivel action is attained as clearly seen in Fig. 15. This swivel mounting allows the iron to tilt to travel over any slight irregularities resulting from the articles to be 10 ironed.

Around the second ring 41 a pair of conducting rings 43 are secured and each ring has a sliding contact member 44 for the electric current for the heating element 45 as shown in Fig. 15 16. These conducting rings revolve with the arm 5 and in this way the iron may be rotated through 360° with current at all times flowing to the heating element.

The handle 46 of the iron is held on the fork 20 47 which is secured on the iron by means of a spindle 48. This spindle is secured to the fork by a screw 49 and to the iron 6 by a bushing 50 and pin 51, Fig. 6. As seen in this figure, the spindle 48 does not extend to the bottom plate 25 of the iron in order to permit vertical movement of the handle 46, fork 47, and spindle 48 relative to the iron. The screw 49 is sufficient to tightly hold the fork 47 to the spindle 48 so that both will rotate together but if desired to guard against 30 any slippage a ball 48' may be inserted between these members, and this ball acts as a key. A ball-bearing 52 between the ring 41 and the bushing permits the iron 6 together with the fork 47 and handle 46 to be rotated 360° on the arm 5. 35 A cover 53 is provided under the fork which is stationary and which has a slot 54 therein for the arm 5.

The end of the lever 14 is connected to one end of a short lever operator 55 pivoted in the arm 40 portion 11 at 56 of which the other end terminates into a ball 57 in the iron. As shown in Figs. 4 and 5 a slot connection 58 is provided for the operator 55 and the lever 14 in order to change directions of the stroke, as a downward 45 movement of the iron handle must result in an upward pull of the operating link 19.

The operation of the device is as follows:

When an operator pushes the iron down which results by merely resting the weight of the hand 50 or the hand and arm on the handle 46, the iron 6, arm 5 and the iron operator 21 move downwardly as a unit. The operator 21 moves in accordance with the member 21 as illustrated by Figs. 11 to 13. In the position of Fig. 13, the iron 55 is on the board and upon further downward movement of the handle 46 a downward movement of the fork 47 slightly rotates the lever operator 55 around pivot 56. This rotates the lever 14 around pivot 15 causing a downward travel of the pull rod 18 and a slight rotation of the lever 16 which in turn pulls the operating rod 19 upwardly. This latter results in the members 29 and 27 assuming a position shown in Fig. 14 from the position of Fig. 13. 60 The spring 29 will now exert a downward pull on the operator 21 which exerts a downward force on the iron 6 by means of the arm 5 as long as the operator's hand exerts a slight force on the handle 46. Upon releasing this force on 65 the handle 46 the various elements reverse their movements so that the spring 29 will restore the parts 22, 5 and iron 6 to the position shown in Figs. 3 and 12.

As shown in Figs. 6 and 7 the electric cord 60 75

may be passed through the arm 5 from the plug 61 to the contact rings 43.

I claim as my invention:

1. A mechanical ironing device comprising an iron and an arm on which the iron is mounted, a jointed parallelogram device on which the arm is mounted and having means associated therewith to apply an ironing pressure to the iron, and means operable from the iron by movement with respect to the arm and to the parallelogram device to apply pressure on the iron through the arm by means of the parallelogram device when the iron contacts an ironing board or the material to be ironed.
2. A mechanical ironing device comprising an iron, an arm on which the iron is mounted, a handle mounted for movement with respect to said iron, a jointed parallelogram device to one link of which the arm is rigidly secured and having means to counterbalance the weight of the iron or to apply ironing pressure on the iron, and means operable by movement of the handle with respect to the iron to remove the influence of the counterbalance and to apply ironing pressure on the arm and iron when the iron contacts an ironing board or the material to be ironed.
3. A mechanical ironing device according to claim 2, in which the last-mentioned means consists of a linkage system in the arm.
4. A mechanical ironing device according to claim 2, in which means is provided on the handle and in the iron to permit vertical movement of the handle relative to the iron, and in which the second-mentioned means consists of a linkage system operable by the movement of the handle.
5. A mechanical ironing device according to claim 2, in which the first-mentioned means includes a spring.
6. A mechanical ironing device according to claim 2, in which the first-mentioned means includes a spring, and in which the last-mentioned means includes a plurality of links provided in the arm.
7. A mechanical ironing device comprising an iron, a handle mounted for movement with respect to said iron, an arm on which the iron is mounted and suspended over an ironing board, a jointed parallelogram device on which the arm is mounted on one of the members thereof, said jointed parallelogram device having a shiftable spring cooperating with and connected thereto which acts to counterbalance the weight of the iron and its arm when the iron is in a position out of contact with the board, and means passing through the arm and operable by movement of the handle with respect to said arm to actuate the spring when the iron is pushed down to contact the board to remove the influence of the counterbalance and to apply pressure on the arm and iron.
8. A mechanical ironing device according to claim 7, in which an arm is connected at one end to the parallelogram and the spring is connected at one end to one of the members of the parallelogram and the other end to the other end of the last-mentioned arm.
9. A mechanical ironing device for an ironing board, comprising an iron, an arm on one end of which the iron is mounted, a handle movably mounted with respect to the iron, a movable member on which the other end of the arm is mounted, a stationary member mounted on the board, a pair of links interconnecting the movable and stationary members, an arm pivotally mounted on the movable member, a spring secured
- at one end to the last-named arm and to one link at the other end, and acting as a counterbalance for the iron, and means passing through the arm operable by movement of the handle with respect to the iron to actuate the last-named arm to remove the influence of the counterbalance and to cause the spring to apply pressure on the iron when the iron contacts the board by moving said last-named arm.
10. A mechanical ironing device comprising an iron and an arm on which the iron is mounted, a handle movably mounted with respect to the iron, means for supporting the arm including four pivoted members forming a parallelogram, a spring, a link pivotally secured at one end to one of the four members and the other end to one end of the spring, the other end of the spring being connected to one of the other three of the four members and means operatively connected with the handle and the link through the arm and operable by movement of the handle with respect to the iron to shift the spring by said link to counterbalance the weight of the iron and arm in one position and in another position to force the iron on the material to be ironed with ironing pressure by moving said last-named arm.
11. A mechanical movement for changing the direction of a force comprising a member movable in at least two directions, a second member pivoted to the first-mentioned member at a point on said second member, a spring secured at one end to the other end of the second-mentioned member and having the other end pivotally secured to a point against which the force in the spring reacts, said pivot points being relatively movable with respect to each other so that they may be moved close to one another or attain coincidence, and means to restrict said first mentioned member to a parallel ruler motion reactively transmitting the reacting force from the said point to which the spring is secured to the first-mentioned member, said spring acting to impart a force in one direction on the first mentioned member when moving in either of its two limiting positions and when the pivot points are relatively moved close to each other or attain coincidence and the second-mentioned member is shifted around its pivot, a force in a direction opposite to the direction of the first-mentioned force is imparted to the first-mentioned member by the spring.
12. A mechanical movement according to claim 11, in which the spring follows the movement of and moves with the second mentioned member around the pivot point of said spring when the second-mentioned member is shifted around its pivot point.
13. A mechanical ironing device comprising an iron, an arm on which the iron is mounted so that it may be moved transversely over an ironing board in any direction, a universal joint connection between the iron and the arm to permit the iron to pass over any irregularities on the ironing board, a pair of contact rings and sliding contacts to carry electric current to a heating element of the iron, and means so that the iron may be turned through 360° on the arm.
14. A mechanical actuator for ironing devices comprising a stationary member, a movable member, means for interconnecting the members to maintain the members parallel to each other, an arm secured to the movable member and shiftable relative thereto, and tension means secured to the arm and to the first-named means

to force the movable member upwardly and to exert a force downwardly on the movable member capable of producing an ironing pressure when the movable member is in a lowered position and upon shifting of the arm.

5 15. A mechanical actuator for ironing devices comprising a stationary member, a movable member, means for interconnecting the members to maintain the members parallel to each other, shiftable means associated with the movable member, and a spring to force the movable member upwardly and to exert a force downwardly on the movable member capable of producing an ironing pressure when the movable member is in a lowered position and upon shifting of the last named means relative to the movable means.

10 16. An actuator according to claim 14, in which the movable member is provided with a bracket to which the arm is pivotally secured.

15 17. A mechanical actuator for ironing devices comprising a stationary member, a movable member, a plurality of links for interconnecting the members to maintain the members parallel to each other, an arm pivotally mounted on the

movable member, and a spring secured at one end to the arm and at the other end to one of said links to normally force the movable member upwardly and to exert a force downwardly on the movable member capable of producing an ironing pressure when the movable member is forced downwardly and when the arm shifts its position around its pivot.

10 18. An actuator according to claim 16, in which the plurality of links is in the form of a pair of links each pivotally connected at both ends to the members.

15 19. A mechanical movement comprising a pair of members and means to maintain relative parallel movement between the members, a third member pivotally connected to one of said pair of members, and a spring having one end secured to the third member and the other end secured to said means, said spring being maintained under tension at all times by said members and means and adapted, when shifted by said third member to set up forces of different magnitude and direction between said pair of members.

20 EDWIN E. FOSTER.
